UNITED STATES PATENT OFFICE.

OSCAR A. ROSS, OF CHICAGO, ILLINOIS, ASSIGNOR OF ONE-HALF TO C. VALLETTE KASSON, OF CHICAGO, ILLINOIS.

VALVE OR THE LIKE.

1,072,507.

Specification of Letters Patent.

Patented Sept. 9, 1913.

Original application filed July 19, 1907, Serial No. 384,547. Divided and this application filed June 15, 1910. Serial No. 566,900.

To all whom it may concern:

Be it known that I, OSCAR A. ROSS, a citizen of the United States, residing at Chicago, in the county of Cook and State of Illinois, have invented certain new and useful Improvements in Valves or the Like, of which the following is a description.

My invention belongs to that general class of devices known as valves and relates particularly to an electropneumatic valve, and has among its objects the production of a simple, efficient, durable and satisfactory device of the kind described that is not easily rendered inoperative and which may be used wherever found applicable.

The device is particularly adapted for use on fluid pressure systems as for example, for signaling devices or automatic railway stopping devices or the like, but its use is not confined to these.

To this end my invention consists in the novel construction, arrangement and combination of parts herein shown and described and more particularly pointed out in the claims.

In the drawings wherein like reference characters indicate like or corresponding parts, Figure 1 is a longitudinal sectional view of my preferred form of device showing the valve in closed or normal position, Fig. 2 is a sectional view of the same taken substantially on line 2-2 of Fig. 1, Fig. 3 is an end elevation of the device, a part removed, Fig. 4 is a sectional view taken substantially on line 4-4 of Fig. 1, Fig. 5 is a sectional view of a portion of a slightly modified construction, and Fig. 6 is a detail view in elevation showing the locking means for the casing.

As before stated, the valve is particularly applicable for railway uses, for example, to automatically set the brakes or give a signal, or both. The operation of the valve is controlled by means of a suitable electrical current which may be controlled by an operator and suitable circuit breakers, as for example, by short circuiting the source of energy, as in the third rail system, or by an opening of the circuit as in the isolated track rail system, etc. Complete electrical controlling circuit is not shown.

Referring to the drawings in which my preferred form of device is shown, 1 is a

casing preferably provided with doors 2 which may contain glass sides or windows 3 if desired. The doors are shown hinged to the casing 1, the same being maintained in their closed positions in any suitable way. As most clearly shown in Figs. 1 and 6, the doors are provided with extended parts 5 formed as at 6 through which a lock bolt 4 is passed, and if desired the bolt may be locked in position by means of a padlock 7 or equivalent means. The casing is provided with what may be termed a diaphragm casing or housing 9 extended as at 8 to afford means for connecting the device to the fluid pressure system, as for example, to the train line of the brake system. The housing is shown removably secured to the casing 1 by means of suitable bolts 32 arranged about the flange 31 of the housing. The extended part 8 is provided with an opening 81 therethrough connecting with a chamber 10 in the housing which is connected by an outlet port 11 to the chamber 12 opening into the outlet 13. The outlet or port 11 is normally-covered or closed and the passage of fluid therethrough controlled by means of a valve 14 arranged to seat on the valve seat 14¹. An auxiliary port 15 opening into the outlet 16 may also be provided, and if desired, suitable whistles 94 and 95 or other signal apparatus be also provided. The signal members or whistles 85 are connected to the outlets 13 and 16 by means of suitable piping 96 and 97 respectively, or equivalent means.

The amount of air or fluid discharged through the outlet 13 may be regulated as hereafter described by means of an adjustable plug 17 or its equivalent, which may be locked by a bolt or rod 18 passing through the openings 19, which to prevent loss or removal of the plug by unauthorized persons, 95 may engage the bolt 4 and be thereby locked thereon when the doors 2 are locked in position.

The valve member 14 is provided with a pin 20 arranged to be engaged by an arm or lever 21 which is pivotally carried on a shaft 22 supported by the casing 9, a spring 23 or its equivalent being provided to resiliently maintain the valve member on its seat. As shown, the lever 21 is forked and 100 provided with a small extension 24 arranged

to engage and prevent the resilient member or spring 23 from becoming disengaged or disarranged. Secured to the lever 21 is a member 25 which is provided with an extended end or stud 27 preferably formed as at 28 at the end. The member 25-27 is controlled or operated by means of a diaphragm 29 of suitable material. If desired, a plate 30 may be provided as shown to stiffen and reinforce the diaphragm 29. The diaphragm housing or casing 9 may be provided with a removable cover 33, same being normally secured in position by means of bolts 34 or their equivalents, suitable packing material 35 being employed if desired.

Within the casing 1 is pivotally secured a member 37 by a bolt or pin 38 or its equivalent. The member 37 has a member 39 pivotally secured thereto by a bolt or pin 40, the member 39 being provided with a depression or notch 41 arranged to coöperate with the end 28 of the extended part 27 of the member 25. A rod or bolt 42 is pivotally secured to the free end of the member 39 by means of a pin 44 or its equivalent, the opposite end of the rod 42 being slidably supported by an extension 43 on the casing 1. A spring or resilient member 45 tends to normally force the parts into the positions shown, the tension of the spring being regulated as desired by means of a nut 46 or equivalent means. The casing 1 is also provided with a stop 47 for the free end of the bolt 42. The member 39 also has secured thereto by means of a pin 49 or the equivalent, a bar 48 which is pivotally secured to another bar 50 by means of a bolt or pin 51 or the equivalent, which pin preferably has its ends 51¹ enlarged or formed substantially similar to that most clearly shown in Fig. 4. The free end of the bar 50 is preferably formed as indicated at 52 and arranged to coöperate with the stop 53 on the casing, and if desired, guides 53¹ may be provided therefor. It might be noted that the parts are so arranged that the bars 48 and 50 are normally but not necessarily slightly out of alignment, as shown. Locking members 54 for the bars 48-50 are also provided, the same being pivoted to the extension 43 by means of a pin 55 or its equivalent, the members being preferably formed substantially as shown with extensions 54¹ and connected by a pin 57. They are preferably supported so that when released as hereafter described, the tendency is for them to fall over out of a vertical position. The members 54 are controlled by means of coils 58 provided with cores 59 and an armature 60 which is provided with slots and loosely supported by screws 62 or their equivalent from the frame 63 (see Fig. 1) so that when the coils are not energized the same may drop substantially into the position indicated by the

dotted lines. The armature is provided with a part 61 arranged to coöperate with the pin 57 connecting the members 54.

Any suitable form of binding posts may be provided; as shown, I provide posts 64, 68 and 70 suitably insulated from the casing and from each other, 65 being a conductor secured to post 64, and 71 a conductor secured to post 70, it being understood that these form a part of a controlling circuit previously mentioned but not shown. The post 64 is connected by a conductor 66 to the windings of the coils and the post 68 by a conductor 67 to the opposite end of the windings of the coils. A preferably resilient switch member 69 carried by one of the posts, as shown, post 68, connects the same with the post 70, the resiliency of the same tending to normally throw it into the dotted position indicated in Fig. 1 and break the circuit at post 70. The member 69, however, is normally maintained in closed position and the circuit including the conductor 65 and 71 closed between the binding posts 64 and 70 when the parts are in normal positions by means of a member 72 carried by the armature 60. However, when the circuit is broken and the armature falls, the switch opens and remains open until the parts of the valve are restored to normal positions, as hereafter more fully explained.

The rod 42 is preferably provided with members 73 secured thereto by means of a pin 74 or its equivalent, the purpose of the same being to restore the members 54 and 100 armature, as more fully explained in the operation of the device.

In the modified form of device shown in Fig. 5 and illustrated in my pending application filed July 19, 1907, Serial No. 384,547, 105 a piston valve is substituted for the diaphragm and slide valve. Referring to this figure, 76 represents an extension on the casing for the attachment to the pressure system, 77 being a chamber. A chamber 78 or 110 port is open to the outlet 80 which may be controlled by a plug 17, as heretofore described, the passage of fluid from the chamber 77 to the port or outlet 78 being controlled by the piston valve 79. In this form 115 81 represents the bolt or rod provided with a resilient member 84 and adjustable nut 83, the rod being supported by the extension 82 of the casing. The jointed bars 85 and 87 are pivotally secured to each other, as 120 88-88, as in the other form of device mentioned, and the end of the bar 85 pivotally secured by means of a screw 86 or the equivalent to member 81¹ arranged on the rod 81. The members 90 represent the members 54 shown in the other form, the same being pivotally secured to the extension 82 by means of a pin 91 or the like. The 125 operation of this form of device will be more fully explained hereafter.

The operation of the valve shown in Figs. 1 to 4 when applied to a fluid pressure system, as for example, to the brake system, may be briefly described as follows, it being understood that the operative parts are shown in normal or restored positions, the dotted lines showing parts 60, 54, 48 and 50 in their positions after the current controlling the coils has been interrupted or reduced in potential and the valve opened.

By referring to Fig. 1, it will be noted that the jointed bars 48 and 50 are nearly in alinement. The pressure of the fluid or air in the train pipe connected to the part 15 impinging upon diaphragm 22 forces the diaphragm and member 27 back against the member 29 and the lever 29 forces the jointed bars 48 and 50 against the stop 53 on the casing 1 and also compresses spring 45. The port 11 is therefore closed and no air can escape from the train line except through operation of the engineer's valve. As before mentioned, the parts are in normal position and this is only by reason of current passing through the coils 58 which hold the armature 60 against the pole faces 59, thus holding the weighted members 54 in vertical position and locking the bars 48 and 50 in the positions shown by the lugs or extensions 56, engaging the part 51 of the pin or bolt 51. Should the coils be deprived of current by short circuiting or a reduction of potential of their source of energy, as in the third rail system or by an opening of the circuit as in the isolated track system or in any other manner, the armature 60 will fall, thus carrying down the parts 54 so that they will fall and by so doing release the bars 48 and 50 as well as forcing them up by means of the extension 54. However, they are positively raised by the extension 54 only after the lugs 56 have cleared the parts 51. The lower end of the lever 29 now moves to the right under the pressure from the diaphragm 22 which also with its parts moves to the right, thus causing the slide valve 14 to uncover the port 11. The train pipe air will now escape through the port 11 and blow the warning whistle 94. The adjustment of the plug 17 is preferably such that with the engineer's brake valve in running position, it will cause service application to be applied upon operation of the valve. It will be noted, however, that by adjustment of spring 45 any desired reduction of train pipe pressure can be obtained and thus any degree of brake application may be applied.

It will be observed that when the armature 60 has lowered a small distance, it will allow the circuit breaking spring 69 to leave the post 70, thus opening the circuit through the coils 58. This operation is very rapid, some tests showing that the circuit is opened in approximately 1/125th of a second. The

circuit cannot now be closed through the coils again until the valve has been restored.

The restoration of the valve is substantially as follows: After the valve has been opened or train has been stopped by full service application, the train pipe pressure may approximate 50 lbs. for example, and the diaphragm 22 under pressure of the spring 45 will actuate the slide valve 14 to maintain this pressure. The engineer now brings his brake valve to lap and thence to service and allows a further reduction, say, of about 10 lbs. so that it will allow the pressure of the spring 45 to overcome the diaphragm pressure so that the operative parts will move to the left. This operation allows the jointed bars 48 and 50 to fall into position in alinement or nearly so, and the continued movement to the left then draws the jointed bars 48 and 50 away from the stop 53 and also permits the valve to uncover the port 11 and at the same time raises the levers or arms or members 54 to the vertical position by means of the lugs 73. The port 15 being open the small whistle 95 is blown indicating that the valve is restored. It will be noted that as the levers or arms 54 rise to the vertical position they carry the armature 60 up to the pole faces 59 and in the last movement of the armature 60 the circuit member 69 is brought to contact with the post 70, thus restoring the circuits through coils 58 which will retain the armature 60 in normal position provided the circuit has been otherwise restored to normal.

The engineer now recharges his train pipe to normal pressure, which causes the diaphragm to force the jointed bars 48 and 50 back against the stop 53, thus closing the port 15. The bars 48 and 50 being in operative positions and locked under the lugs 56 maintain the valve in normal or restored position until the next operation of the valve. If, however, the electrical circuit controlling the coils has not been restored to normal the valve will be immediately operated, as before described. The adjustable plug or member 17 may be adjusted for any range of service application or emergency that may be desired, or it may be so regulated that the warning whistle will blow without applying the brakes, although a full service application must be made before the electro-pneumatic valve can be restored as described.

The operation of the modified construction shown in Fig. 3 is substantially similar except that the pressure of the fluid in the system is directly on the valve member 79 and rod 81 instead of communicated thereto through a diaphragm and levers, the valve being of the piston type instead of the slide valve shown in the other form. With this form the signal mechanism or whistle 94 may be also employed if desired.

Having thus described my invention it is obvious that various immaterial modifications may be made in the same without departing from the spirit of my invention, hence I do not wish to be understood as limiting myself to the exact form, arrangement, construction or combination of parts herein shown or described or uses mentioned.

What I claim as new and desire to secure by Letters Patent is:

1. In a fluid pressure system, a valve, electrically controlled means independent of the system for normally maintaining said valve in operative position and means controlled by the pressure in the system for operating said valve or restoring the same to operative position.
  2. In a fluid pressure system, a valve, means controlled by the pressure in the system for operating said valve or restoring the same after the operation and electrically controlled means independent of the pressure system for normally preventing the operation or complete restoration of said valve.
  3. In a device of the kind described, a casing provided with an outlet, means for attaching said casing to a fluid pressure system, a normally closed valve for controlling said outlet, means controlled by the pressure in said system for operating said valve, in combination with means for rigidly maintaining said valve in its normal position and independently controlled means arranged when operated to release said valve.
  4. In a device of the kind described, a casing provided with an outlet, means for attaching said casing to a fluid pressure system, a normally closed valve for controlling said outlet, means controlled by the pressure in said system for operating said valve, and auxiliary independently controlled means for controlling the discharge of fluid through said outlet, in combination with means for rigidly maintaining said valve in its normal position and independently controlled means arranged when operated to release said valve.
  5. In a device of the kind described, a casing provided with an outlet, means for attaching said casing to a fluid pressure system, a normally closed valve for controlling said outlet, means controlled by the pressure in said system for operating said valve, and auxiliary adjustable means operable in conjunction with said valve for controlling the discharge of fluid through said outlet, in combination with means for rigidly maintaining said valve in its normal position and independently controlled means arranged when operated to release said valve.
  6. In a device of the kind described, a casing, means for attaching said casing to a fluid pressure system, an outlet for permitting the escape of fluid from said sys-
- tem, a normally closed valve for controlling said outlet, means controlled by the pressure in said system for actuating said valve, in combination with means for rigidly maintaining said valve in its normal position and means controlled by a closed electric circuit arranged to release said valve on a suitable reduction of said circuit potential.
7. In a device of the kind described, a casing, means for attaching said casing to a fluid pressure system, an outlet for permitting the escape of fluid from said system, a normally closed valve for controlling said outlet, resiliently opposed means controlled by the pressure in said system for actuating said valve, in combination with means for rigidly maintaining said valve in its normal position and means controlled by a closed electric circuit arranged to release said valve on a suitable reduction of said circuit potential.
8. In a device of the kind described, a casing, means for attaching said casing to a fluid pressure system, an outlet for permitting the escape of fluid from said system, a normally closed valve for controlling said outlet, means controlled by the pressure in said system for actuating said valve, adjustable means for resiliently opposing the operation of said actuating means, in combination with means for rigidly maintaining said valve in its normal position and means controlled by a closed electric circuit arranged to release said valve on a suitable reduction of said circuit potential.
9. In a device of the kind described, a casing, means for attaching said casing to a fluid pressure system, an outlet for permitting the escape of fluid from said system, a normally closed valve for controlling said outlet, means controlled by the pressure in said system for operating said valve, in combination with means for rigidly maintaining said valve in its normal position, means controlled by a closed electric circuit arranged to release said valve on a suitable reduction of said circuit potential, and means for interrupting said circuit when the potential becomes so reduced.
10. In a device of the kind described, a casing, means for attaching said casing to a fluid pressure system, an outlet for permitting the escape of fluid from said system, a normally closed valve for controlling said outlet, resiliently opposed means controlled by the pressure in said system for operating said valve, in combination with means for rigidly maintaining said valve in its normal position, means controlled by a closed electric circuit arranged to release said valve on a suitable reduction of said circuit potential, and means for interrupting said circuit when the potential becomes so reduced.
11. In a device of the kind described, a valve for controlling an outlet from a fluid

- pressure system and means for retaining said valve in its closed position, means including a closed electrical circuit for releasing said valve upon a suitable reduction of the potential of said circuit and co-operating means adapted to interrupt said circuit when the potential becomes reduced.
12. In a device of the kind described, a valve for controlling an outlet from a fluid pressure system and means for retaining said valve in its closed position, means including a closed electric circuit for releasing said valve upon a suitable reduction of the potential of said circuit and co-operating means adapted to interrupt said circuit upon operation of the valve.
13. In a device of the kind described, a casing, means for attaching said casing to a fluid pressure system, a valve positioned within said casing and means operable by the pressure in the system for opening said valve when released, in combination with valve controlling mechanism adapted to normally prevent the operation of said valve opening means, means for operating said mechanism to release said valve and means for closing said valve and automatically resetting said valve controlling mechanism.
14. In a device of the kind described, a casing, means for attaching said casing to a fluid pressure system, a valve positioned within said casing and resiliently opposed means operable when released by the pressure in the system for opening said valve, in combination with valve controlling mechanism adapted to normally prevent the operation of said valve opening means, means for operating said mechanism to release said valve and means for closing said valve and automatically re-setting said valve controlling mechanism.
15. In a device of the kind described, a casing, means for attaching said casing to a fluid pressure system, a valve positioned within said casing and means operable by the pressure in the system for opening said valve when released to permit the escape of fluid from said system, in combination with valve controlling mechanism arranged to normally prevent the operation of said valve opening means, means for operating said mechanism to release said valve and means controlled by the pressure in the system for automatically closing said valve and re-setting said controlling mechanism.
16. In a device of the kind described, a casing, means for attaching said casing to a fluid pressure system, a valve positioned within said casing and means operable by the pressure in the system for opening said valve when released to permit the escape of fluid from the system, in combination with valve controlling mechanism comprising a jointed bar operatively attached to said valve to normally prevent the opening there-
- of, means controlled by an electro-magnet for preventing the deflection of said bar to release said valve and means controlled by the pressure in the system for closing said valve and automatically re-setting said valve controlling mechanism.
17. In a device of the kind described, a casing, means for attaching said casing to a fluid pressure system, a valve positioned within said casing and means operable by the pressure in the system for opening said valve when released to permit the escape of fluid from the system, in combination with valve controlling mechanism comprising a jointed bar operatively connected to the valve and arranged to prevent the opening thereof, a latch, electro-magnet controlling means for said latch, said latch arranged to engage said bar and prevent the deflection thereof and when released to positively deflect the same to release said valve, resilient means tending to automatically close said valve when the pressure in the system is sufficiently reduced and to return said latch into position to control said bar and to be controlled by said electro-magnet.
18. An electro-pneumatic valve of the kind described, comprising a casing, a valve, fluid operable actuating mechanism for said valve and co-operating means arranged to restore the same after operation upon variation of the fluid pressure in the system and independently controlled means for normally maintaining the actuating mechanism and valve in operative position.
19. An electro-pneumatic valve of the kind described, comprising a casing provided with an inlet and an outlet port, a valve arranged in said casing arranged to control said outlet port, adjustable means for resiliently opposing the operation of said valve, fluid operable actuating means for said valve comprising a diaphragm and means for operatively connecting said diaphragm and valve, means for normally maintaining the actuating mechanism and valve in operative position, and independently controlled means for maintaining said locking means in operative position and auxiliary adjustable controlling means for said port.
20. An electro-pneumatic valve of the kind described, comprising a casing, provided with an inlet and outlet port, a slide valve arranged within said casing arranged to control said outlet, fluid operable actuating means for said valve and means for normally positively locking and preventing the operation of said actuating means.
21. An electro-pneumatic valve of the kind described, comprising a casing, provided with an inlet and outlet port, a valve arranged within said casing arranged to control said outlet, fluid operable actuating means for said valve and locking means for normally preventing the operation of said

- actuating means, said means comprising a jointed bar and means for releasing said locking means,
22. An electro-pneumatic valve of the kind described, comprising a casing, provided with an inlet and outlet port, a valve arranged within said casing arranged to control said outlet, fluid operable actuating means for said valve and locking means for normally preventing the operation of said actuating means, said means comprising a jointed bar and means for releasing said locking means, comprising independently electrically controlled means,
23. An electro-pneumatic valve of the kind described, comprising a casing, provided with an inlet and outlet port, a valve arranged within said casing arranged to control said outlet, fluid operable actuating means for said valve and means for normally preventing the operation of said actuating means, said means comprising a jointed bar and means for releasing said locking means, and means for restoring said locking means to operative position,
24. An electro-pneumatic valve of the kind described, comprising a casing provided with an inlet and with an outlet port, a controlling valve for said outlet port, fluid operable actuating means for said valve and
- 5 coöperating means arranged to restore the same after operation upon variation of the fluid pressure in the system comprising a resilient member means for operatively connecting said resilient member and actuating means and means for locking the same in restored position.
25. In a fluid pressure system, a casing provided with an inlet and outlet port, a valve for said outlet port arranged within said casing, fluid operable actuating means for said valve and independently controlled means for normally maintaining the actuating mechanism and valve in operative position, comprising a jointed bar and independent electrically controlled means for maintaining said bar in operative position, comprising a pair of connected pivotally supported gravity latch members, a plurality of coils, a pivorially supported armature controlled by said coils and means for operatively connecting said latch members and armature.
- In testimony whereof, I have hereunto signed my name in the presence of two subscribing witnesses.
